UNITED STATES PATENT OFFICE.

JOSEPH LEDWINKA, OF PHILADELPHIA, PENNSYLVANIA, ASSIGNOR TO EDWARD G. BUDD MANUFACTURING COMPANY, OF PHILADELPHIA, PENNSYLVANIA, A CORPORATION OF PENNSYLVANIA.

LATCH MECHANISM.

Application filed August 27, 1921. Serial No. 493,042.

To all whom it may concern:

Be it known that I, JOSEPH LEDWINKA, a citizen of the United States, residing at Philadelphia, Pennsylvania, have invented 5 certain new and useful Improvements in Latch Mechanism, of which I declare the following to be a full, clear, and exact description.

My invention relates to improvements in 10 latch mechanism, and has to do, more particularly, with latch mechanism for use in connection with automobile doors.

One of the principal objects of my invention is to provide an improved latch mechanism 15 which will require the application of only a very slight pressure or force, to the door in closing it, in order to retract the latch bolt.

Another object of my invention is to provide 20 an improved latch construction in which friction between the relatively moving parts is very largely reduced or eliminated.

Another object of my invention is to provide 25 an improved latch construction in which the latch bolt will be securely retained in locking position by engagement with the keeper, without the necessity for employing comparatively stiff or strong springs for that purpose.

Another object of my invention is to 30 provide an improved latch construction in which a swinging latch bolt is withdrawn from locking position by the actuation of a slideable bolt-operating member.

Further objects, and objects relating to 35 details and economies of construction and operation, will definitely appear from the detailed description to follow. My invention is clearly defined and pointed out in the appended claims. A structure constituting a preferred embodiment of my invention is 40 illustrated in the accompanying drawings, forming a part of this specification, in which:

Figure 1 is a plan view of a latch embodying my invention.

Fig. 2 is a view of the latch in side elevation.

Fig. 3 is a transverse, sectional view through the latch, taken on the line 3—3

of Fig. 1, and showing the operating spindle 50 and handles.

Fig. 4 is a sectional view on the line 4—4 of Fig. 3, showing the parts for actuating the bolt-operating member.

Fig. 5 is a sectional view taken on line 55 5—5 of Fig. 1, and

Fig. 6 is a perspective view of the bolt-operating member.

In the drawings, the same reference number refers to the same part throughout the 60 several views, and the sectional views are taken looking in the direction of the arrows at the ends of the section lines.

It is among the special purposes of my invention to provide a latch bolt which is pivotally mounted to swing into and out of locking position, and which is so arranged that when in locking position the locking strain 65 of the keeper is taken by the pivot stud of the latch bolt in a direction radially towards the axis of the said stud, thereby relieving the operating devices for the latch bolt from such strains. To accomplish this result in one form of embodiment of my invention, the end surface of the swinging latch bolt 70 is curved to an arc concentric with the pivotal axis of the latch bolt and this curved surface is engaged by the keeper when the latch bolt is in locking position. Normally,

in accordance with my invention, the latch 75 bolt is yieldingly maintained in position for its forward side surface to engage the keeper in the closing movement of the door whereby the latch bolt is rocked upon its pivot thereby being depressed to permit the 80 curved end surface of the bolt to come into locking engagement with the keeper; and I propose to provide means to impose only

a slight yielding resistance to this depressing movement of the latch bolt and hence only 85 a very slight pressure or force is required to be applied to the door in closing it, and in bringing the latch bolt into locking position, thereby attaining one of the principal objects and purposes of my invention.

By imposing the strain of the locking engagement of the latch bolt and keeper, when the door is in closed position, upon

the pivot of the latch bolt, I am enabled to eliminate and avoid the use of stiff or strong springs for taking such strains, while at the same time securely retaining 5 the lock in its locking position.

It is also among the special purposes of my invention to provide operating means for the latch bolt, which, while permitting the yielding swinging movement of the latch 10 bolt, above referred to, during the closing movement of the door, may be operated by suitable handles, easily and readily, and with the expenditure of only small force, to effect a manual withdrawal of the latch 15 bolt from locking position when it is desired to open the door. To accomplish this result, in accordance with my invention, I propose to employ means suitably connected to the swinging latch bolt, and which are 20 mounted to slide rectilinearly in a direction tangential to the arc of swing of the latch bolt, and I propose to reduce to a minimum the area of surface contact of the sliding parts in order to reduce the friction of such 25 sliding movement.

I also provide a simple arrangement of manually operable means to effect the withdrawal of the latch bolt from its locking position, whenever desired, to effect the 30 opening of the door. To this end I propose to employ a roll-back member arranged to engage the latch bolt-operating connections, and yieldingly held in its normal position in which it permits the latch 35 to be maintained in its locking position.

These various objects and purposes may be accomplished in many different ways, and, while I have shown and will now describe an illustrative simple and efficient 40 embodiment of my invention, I wish it to be understood that in the broadest scope of my invention, as defined in the claims, I do not desire to be limited or restricted to the exact details of the structure shown.

In the structure illustrated in the accompanying drawings a base plate 10 is provided having a flange 11 extending laterally from one edge thereof. The flange 11 also has a lip 12 extending from the free 50 edge thereof, parallel to the base plate, for convenience in mounting the latch in the door. A bolt opening 13 is provided in the flange 11 and a swinging latch bolt 17 is mounted so as to swing through said opening. In the structure shown this latch bolt is mounted on a support 14 secured to the base plate 10 near the flange 11 and provided with a pair of ears 15 carrying a pivot pin 16 on which the latch bolt 17 is 55 pivotally mounted. The latch bolt 17, if desired, may be formed into a recess 25 opening through its rear face, so that it is substantially hollow and is thereby correspondingly reduced in weight. The end 60 surface 18 of the latch bolt is curved to

an arc concentric with the axis of the pivot 16, and the front side of the latch bolt lies parallel to a radial plane through said axis. A bolt-operating member 19 is provided for actuating the swinging latch bolt. This 70 bolt-operating member is mounted so as to slide relative to the base plate and it has an extended portion 24 which is pivotally connected to the latch bolt, as by the pin 26. The body portion of the member 19 75 has an elongated, central opening 20, and, at the end opposite the extension 24, a guide lug 21 which works in a slot 22 formed in the base plate 10. The portion of the bolt-operating member 19 adjacent 80 the lug 21, and the corresponding end of the central opening 20, is thicker than the body portion of said member 19, and is provided with the projecting portions 23 on the face 85 thereof which is presented toward the base plate 10, said projecting portions forming shoulders 40. A spring 27 mounted on a post 42 carried by the base plate engages the end of the member 19, adjacent the lug 21, and normally exerts its tension to urge 90 the said member toward the flange 11, so as to swing the latch bolt 17 forwardly on its pivot into projected position as clearly shown in Figs. 1, 2 and 3.

A bridge 30 mounted on the base plate 95 10 extends over the bolt-operating member 19. Any suitable means may be provided to manually retract the bolt. For this purpose I have shown a roll-back 38 which is journaled in the base plate at 100 29, and in the bridge, 30, at 31. The roll-back, 38, in the illustrative form shown, has laterally-extending fingers 39 which work in the space between the base plate 10 and the body portion of the bolt-operating member 19, and normally engage 105 against the shoulders 40. A spring, 28, carried by post, 43, engages the back of the roll-back to restore it to normal position 110 after it has been displaced therefrom in retracting the bolt. The roll-back is provided with a square opening or passage 35 through which extends the square spindle 34, to which the operating handles 36 and 37 are attached. This is one of the 115 customary expedients for actuating a roll-back and it is obvious that other means may be utilized for that purpose. When this latch construction is used in all-metal doors, having two spaced panels between which 120 the latch is inserted, I provide a support, 32 for one of the escutcheon plates, which is secured to the bridge 30 at 33, and has a central opening through which the spindle 34 extends. The latch mechanism 125 operates with the usual keeper (not shown). When the door, carrying this latch mechanism, is swung to closed position, the edge of the keeper engages the front side or edge 130 of the swinging latch bolt 17. The resist-

ance offered to the closing movement of the door by the keeper tends to swing the latch bolt 17 on its pivot 16 and the greater portion of this force is resolved into a component in the direction of the length of the bolt-operating member 19, tending to slide it along the base plate 10, against the pressure of the spring 27. It will be noticed that the only forces tending to resist this movement are the pressure of the spring 27, the friction between the latch bolt and its pivot, which friction is very small, and the friction between the bolt-operating member 19 and the bridge 30, and base plate 10 at the points where said member is guided by such parts. This latter friction is reduced because the area of the parts in surface contact is greatly reduced, the only portion of the bolt-operating member 20 having such sliding contact being the thicker portion adjacent the lug 21. Furthermore, it will be observed that the pressure applied in closing the door when the front face of the latch bolt engages the keeper, 25 is translated into a force acting in the direction of the length of the bolt operating member and hence there is no tendency, as in the ordinary sliding-bolt construction, to press the bolt-operating member toward 30 one of the parts on which it slides, which otherwise would increase the sliding friction. When the door in closing has moved sufficiently far to permit the edge of the keeper to pass the outer end of the latch bolt 17, and to receive the arc surface of 35 the latch bolt thereagainst, the spring 27 acting on the bolt-operating member 19, swings the latch bolt forwardly to and maintains the same in its normal locking position with the keeper in engagement with the end surface 18 of the latch bolt. When 40 in this position, a force exerted on the door in the direction to open it is applied to the end of the latch bolt in a direction radial of its pivot, the resulting strain is taken by the latch bolt pivot and is not imposed upon the bolt-operating member 19. Consequently, a very light spring is all that is 45 needed to maintain the bolt-operating member 19 in locking position. When it is desired to retract the latch, the operating spindle 34 is turned in either direction by one or the other of the handles 36, 37. This causes one or the other of the fingers 39 50 of the roll-back to press against a shoulder 40 on the bolt-operating member 19, and slides said member back against the tension of spring 27, thereby retracting the latch bolt through the opening 13 out of engaging 55 relation with the keeper on the door jamb. The spring 28, acting on the flat back of the roll-back, restores it to normal position when the handle is replaced and the spring 27 presses the bolt-operating 60 member 19 to its normal position to again 65

project the latch bolt through the opening 13 and into the projected position shown in the drawings.

By reducing the friction as described and by providing a construction in which only 70 a light spring is needed to project the bolt, I have attained objects of my invention and produced a latch which is remarkably sensitive, that is to say, a very slight force applied to the door will be sufficient to 75 latch it.

What I claim as new and useful and of my own invention, and desire to secure by Letters Patent is:

1. A latch mechanism comprising a base plate, a swinging latch bolt mounted thereon, a bolt-operating member slidably mounted on said base plate and provided with a lug sliding in a slot therein, the body portion of said member being spaced from the base plate, said member being connected to said latch bolt, a rotatable roll-back engaging said bolt-operating member to actuate the same, and means for rotating said roll-back. 80

2. A latch mechanism comprising a base plate a swinging latch bolt mounted thereon, a bolt-operating member connected to said latch bolt and having its body portion spaced from said base plate but guided for sliding movement thereby, a roll-back positioned between said base plate and the body portion of said bolt-operating member and engaging said member to actuate the same, and means for operating said roll-back. 95

3. A latch mechanism comprising a base plate, a swinging latch bolt mounted thereon, a bolt-operating member connected to said latch bolt and having its body portion spaced from said base plate but guided for sliding movement thereby, the body portion of said member being provided with a central opening, a roll-back extending through said central opening and having portions working between the body portion of said bolt-operating member and the base plate and engaging said bolt-operating member to actuate the same, and means for operating said roll-back. 105

4. A latch mechanism comprising a base plate, a swinging latch bolt mounted thereon, a bolt-operating member connected to said latch bolt and having its body portion spaced from said base plate but guided for sliding movement thereby, the body portion of said member being provided with a central opening and projecting shoulders on each side thereof, a roll-back extending through said central opening and having portions working between the body portion of said bolt-operating member and the base plate and engaging said projecting shoulders to actuate the bolt-operating member, and means for operating said roll-back. 110

5. A latch mechanism comprising a base 120

plate, a swinging latch bolt mounted thereon, a bolt-operating member connected to said latch bolt and having its body portion spaced from said base plate but guided for 5 sliding movement thereby, the body portion of said member being provided with a central opening, projecting shoulders on each side thereof, and a lug sliding in a slot provided in said base plate, a roll-back extending 10 through said central opening and having portions working between the body portion of said bolt-operating member and the base plate, and engaging said projecting shoulders to actuate the bolt-operating member, and means for operating said roll-back.

6. A latch mechanism comprising a base plate, a swinging latch bolt mounted thereon, a bolt-operating member connected to said latch bolt and having its body portion 20 spaced from said base plate but guided for sliding movement thereby, the body portion of said member being provided with a central opening, projecting shoulders on each side thereof, and a lug sliding in a slot provided in said base plate, a roll-back extending 25 through said central opening and having laterally extending fingers working between the body portion of said bolt-operating member and the base plate and engaging said 30 projecting shoulders to actuate the bolt-operating member, and means for operating said roll-back.

7. A latch mechanism comprising a base plate, a latch bolt pivotally mounted on said 35 base plate, a bolt-operating member mounted on said base plate to slide in a right line and pivotally connected to said latch bolt, a roll-back engaging said bolt-operating member to actuate it in one direction, a 40 spring engaging said bolt-operating member to actuate it in the opposite direction, a spring engaging said roll-back to restore it to normal position, and means for operating said roll-back.

45 8. A latch mechanism comprising a base plate, a swinging latch bolt pivotally mounted on said base plate, a bridge mounted on said base plate, a bolt-operating member connected to said latch bolt and slidably be- 50 tween said bridge and base plate, a roll-back journaled in said bridge and base plate and engaging said bolt-operating member to actuate it in one direction, and means for operating said roll-back.

55 9. A latch mechanism comprising a base plate, a swinging latch bolt pivotally mounted on said base plate, a bridge mounted on said base plate, a bolt-operating member pivotally connected to said latch bolt and 60 guided for sliding movement between said bridge and base plate, said bolt-operating member having a body portion spaced from said bridge and base plate and a thicker portion having sliding contact therewith, 65 and shoulders projecting from said thicker

portion toward the base plate, a roll-back journaled in said bridge and base plate and having fingers working between said bolt-operating member and the base plate and engaging said shoulders to actuate the bolt-operating member in one direction, and means for operating said roll-back.

10. A latch mechanism comprising a base plate, a swinging latch bolt pivotally mounted on said base plate, a bridge mounted on 75 said base plate, a bolt-operating member pivotally connected to said latch bolt and guided for a sliding movement between said bridge and base plate, said bolt-operating member having a body portion spaced from 80 said bridge and base plate, a thicker portion having sliding contact therewith, and shoulders projecting from said thicker portion toward the base plate, the body portion of said member being provided with a central 85 opening, a roll-back extending through said central opening and journaled in said bridge and base plate, said roll-back having fingers working between said bolt-operating member and the base plate and engaging said 90 shoulders to actuate the bolt-operating member in one direction, and means for operating said roll-back.

11. A latch mechanism comprising a base plate, a swinging latch bolt pivotally mounted on 95 said base plate, a bridge mounted on said base plate, a bolt-operating member connected to said latch bolt and slidably between said bridge and base plate, a roll-back journaled in said bridge and base plate and engaging said bolt-operating member to actuate it in one direction, an escutcheon 100 support carried by said bridge, and means for operating said roll-back.

12. A latch mechanism comprising a base plate, a latch bolt pivoted thereon, a bolt operating member connected to said latch bolt and slidably mounted on said base plate, guide means on said member cooperating with the base plate, said member being 105 out of contact with said base plate except for a limited area adjacent said guide means, and means for actuating said bolt operating member.

13. A latch mechanism comprising a base 115 plate provided with a slot therein, a latch bolt pivoted on said base plate, a bolt operating member pivotally connected to said latch bolt and having a lug sliding in said slot, the body portion of said member being 120 out of contact with said base plate except for a limited area adjacent said lug, and means for actuating said member.

14. A latch mechanism comprising a base plate having a slot therein, a latch bolt 125 pivoted on said base plate, a sliding bolt operating member pivotally connected to said latch bolt and having a lug working in said slot, said member being out of contact with said base plate except for a limit- 130

ed area adjacent said lug, a spring engaging said member adjacent said lug to project the latch bolt, and means for retracting said member against the pressure of said spring.

5 15. A latch mechanism comprising a base plate, a latch bolt pivoted thereon, a bridge member fastened to said base plate, a bolt operating member pivotally connected to said latch bolt and sliding between said

bridge and base plate, guide means on said member cooperating with the base plate, said member being out of contact with said base plate and bridge except for limited areas adjacent said guide means, and means

for actuating said member. 15

In testimony whereof, I affix my signature.

JOSEPH LEDWINKA.
